UNITED STATES PATENT OFFICE.

ELMER A. SPERRY, OF BROOKLYN, NEW YORK.

GRAVITY BOMB.

Application filed October 14, 1921. Serial No. 507,591.

This invention relates to gravity bombs, especially those provided with means for changing their path of descent, such as shown in the patent to E. A. Sperry and T. H. Philips, Jr., No. 1,384,868, July 19, 1921, for "dirigible gravity bomb." In order to render practicable the controlling of the path of descent of such bombs at the will of a distant operator there is disclosed in 10 said patent means for returning the bomb to a predetermined position about its vertical axis in case it departs therefrom, i. e., stabilizing the bomb in azimuth. One of the objects of the present invention is the provision of a novel and improved means for stabilizing the bomb in azimuth, which shall be simple in construction and at the same time highly efficient and reliable in operation. The stabilizing means which I have devised 15 comprises control planes at the circumference of the drag rudder, where a maximum turning effect may be secured, and gyroscopic means carried outside of the bomb for automatically controlling said planes to 20 cause the return of the bomb to a given position about its vertical axis when the bomb departs from such position.

Another object is the provision of a stabilizing system utilizing pneumatic means, 30 gyroscopically controlled, for causing actuation of said control planes.

A further object of my invention is to provide novel and improved means, involving a minimum number of parts for automatically spinning up and unlocking the 35 gyroscope during the opening of the drag rudder.

Both the gyroscope and the spinning up means therefor are positioned within a hollow member to the upper end of which is connected the drag rudder and to the lower end of which may be connected any suitable type of bomb. In the patent above referred to gyroscopic control means and spinning 45 up means are shown carried within the bomb. One of the advantages of positioning said means outside of said bomb is that the latter may carry more explosive than was heretofore possible without increasing the 50 size thereof, so that for a bomb of a given size the destructive effect may be considerably increased. Also for a given amount of explosive the size of the bomb may be reduced to a minimum.

55 Other objects and advantages of my in-

vention will become apparent as the description thereof is hereinafter developed.

Referring to the drawings wherein I have shown what I now consider to be the preferred form of my invention:

Fig. 1 is a vertical sectional view, partly in elevation, of my invention.

Fig. 2 is a vertical sectional view of a detail.

Fig. 3 is a fragmentary plan view showing means for attaching the ribs of the drag rudder to the top of the hollow member above referred to.

Fig. 4 is a vertical sectional view through the upper portion of said hollow member 70 showing the gyroscopic stabilizing means and the means for spinning up and unlocking the gyroscope.

Fig. 5 is a vertical sectional view of a detail of the gyroscopic stabilizing means.

Fig. 6 is a plan view of another detail of the stabilizing means.

At 1 is shown a drag rudder of the type disclosed in the patent referred to, said rudder being in the form of an inverted cone 80 and serving both to retard the descent of the bomb, and when deflected, to steer the latter. Said rudder comprises a plurality of ribs 2 to the under sides of which fabric is secured. In said patent is fully disclosed means controllable at the will of a distant operator for tilting the drag rudder for changing the path of descent of the bomb. Such means comprises a ring 80 engaging the upper side of the drag rudder and connected by cords, 90 two of which are indicated at 81, with mechanism inside the bomb for tilting the ring, and hence the drag rudder, in response to wireless impulses transmitted by said operator. Since such mechanism is fully disclosed in said patent and forms no part of the present invention it will not be described here.

The drag rudder is shown secured to the upper portion of a hollow stem or casing 3. 100 For this purpose each of ribs 2 may be provided with a recessed extension 4 which fits in a corresponding one of sockets 5 provided on a ring 6 secured to the upper portion of said casing 3. Said sockets are provided 105 with apertures corresponding with the apertures in the extensions 4 of the respective ribs and a resilient split ring 7 may be passed through the apertures in said sockets and ribs to fasten the ribs to said casing. 110

At its lower end the casing 3 is provided with a flange 8 which may be bolted or otherwise secured to any suitable type of bomb or other missile which is to be dropped.

- 5 I have shown casing 3 secured by said flange to a bomb 9 of the type shown in the above mentioned patent. The flange 8 is shown bolted to brackets 10 which are secured to bomb 9 and which may also support the 10 cylindrical guard 11 of a servo-motor fan 12.

Before the bomb is launched the drag rudder is folded about stem 3, and upon launching of the bomb said drag rudder opens into the position shown in Fig. 1. In 15 order to cushion the drag rudder as it opens and to prevent the too rapid opening thereof, I have provided means for retarding said opening, which means may also be employed to spin up the rotor of the gyroscope which 20 controls the stabilizing of the bomb in azimuth. Such means is shown in Figs. 1, 2, and 3, and may be constructed substantially as follows:

Slidable within casing 3 is a piston 13 having a rod 14 connected at its lower end to a guide rod 15. The latter extends through longitudinal slots 16 in the lower portion of said casing and is connected to a ring 17 which is slidably mounted on the outside of 0 the casing. Ring 17 carries pulleys 18 over which pulleys pass cords 19 connected at one end to the respective ribs 2 and at their other ends to a stationary ring 20. The latter may be supported outside casing 3 by 5 means of rods 21 secured at their upper ends to ring 6 and provided adjacent their lower ends with means for holding said ring 20. By employing the rods 21 to hold said ring I avoid fastening the latter directly to the walls of casing 3 which walls are preferably thin and might be constricted if ring 21 were secured directly thereto, with consequent interference with the motion of piston 13.

When the drag rudder is folded about casing 3 prior to launching, rod 15 and ring 17 are at the bottom of slots 16. Upon the opening of said rudder as the bomb descends ring 17 and piston 13 are raised, the piston thereby compressing air within the casing 3. Thus the opening of the drag rudder is retarded and cushioned. I have provided means for utilizing the air so compressed for spinning up the rotor 23 of gyroscope 22, which means will now be described.

The gyroscope 22 is shown within the upper portion 24 of casing 3, a partition 25 separating said portion from the portion containing piston 13. Said gyroscope comprises a rotor 23 mounted for rotation about a horizontal axis in a ring 26, said ring being pivoted to a vertical ring 27 for movement about a horizontal axis at right angles to the first mentioned horizontal axis. The vertical ring 27 is in turn pivotally mounted

about a vertical axis. A bevel gear 28 is fixed to the shaft of rotor 23 and meshes with another bevel gear 29 fixed to a shaft 30. The latter is slideable within a bearing 31 in portion 24 of casing 3 and carries at 70 its lower end a turbine wheel 37 with which cooperates a nozzle 32. Said nozzle communicates with the portion of casing 3 that contains piston 13, so that as said piston moves upwardly air is forced through the 75 nozzle. A grooved collar 33 is fixed on shaft 30, and a forked lever 34 engages at one end in said groove. Lever 34 is pivoted intermediate its ends to a bracket 35 standing from partition 25. A compression 80 spring 36, interposed between gear 29 and bracket 31 biases said gear into mesh with gear 28. At the same time as said gears are enmeshed, a pin or projection 38 which extends upwardly from shaft 30 is engaged 85 within a corresponding socket 38' fixed to ring 26 and thus locks the gyroscope. Turbine 37 is at this time opposite nozzle 32 so that as the piston 13 moves upwardly said turbine will be rotated to spin up rotor 23. 90 For unlocking the gyroscope after the latter is sufficiently spun up, a plunger 39 may be connected to one end of lever 34, as shown, said plunger extending a short distance through partition 25 and into the path of 95 piston 13. As the latter nears the limit of its upward movement it engages said plunger and moves lever 34 to cause pin 38 to be withdrawn from engagement with socket 38' and gear 29 to be withdrawn from mesh with gear 28. The rotor 24 is by that time spun up and thereupon the gyroscope assumes control of the azimuth stabilizing means. Openings 40 may be provided in section 24 of casing 3 to permit the escape 105 of the air which has been employed to rotate turbine wheel 37.

The means for stabilizing the bomb in azimuth comprises control planes carried by the drag rudder, the gyroscope 22, and 110 means controlled by said gyroscope for actuating said control planes. Two control planes 41, 42, are shown at diametrically opposite points of the circumference of the drag rudder, said planes being secured to 115 rods 43, 44 respectively, which rods are rotatably mounted within suitable grooves in certain of the ribs of the drag rudder. The planes 41, 42 are shown positioned just beyond the circumference of said drag rudder. 120 The location of said planes at the circumference of the drag rudder is decidedly advantageous, since; (1) said planes are thereby rendered highly efficient due to the wide radius and large leverage over the load; (2) said planes may be made small owing to their high efficiency; and, (3) said planes, being just beyond the perimeter of the drag rudder are at the point of the most rapid 125 sweep of air, still further increasing their 130

efficiency. If desired, the number of control planes may be increased. For example, an additional set of such planes may be provided at 90 degrees from planes 41 and 42, 5 one of the planes of said additional set being shown at 46, secured to a rotatable rod 47. The rotation of each of the rods 43, 44, 47 is controlled from gyroscope 22. While said rotation might be controlled from said 10 gyroscope by electrical means I have shown pneumatic means for this purpose, the gyroscope causing the actuation of bellows 48, 48', and 50. These bellows are carried by the ribs of the drag rudder and are similar 15 in construction, each comprising a central movable member connected to the corresponding control plane operating rod, on the opposite sides of which member are expandable chambers. Thus, as shown in connection 20 with bellows 50, the end walls 51 and 52 are stationary and the intermediate movable member 53 is secured to rod 47. Between member 53 and wall 51 is an expandable chamber 54, while between said member 25 53 and wall 52 is another expandable chamber 55. It will be readily understood from this construction that member 53 may be moved to one side or the other by expanding one or the other of chambers 54, 55, and that 30 plane 46 may thus be turned in its proper direction. The operation of bellows 48, and 48' to move the corresponding control planes is similar to that above described. An additional bellows similar to those above described is shown at 50' for operating rod 49 to control the plane (not shown) diametrically 35 opposite plane 46.

The gyroscope 22 controls the admission of compressed air to the respective bellows 40 so that whenever the bomb turns about a vertical axis away from its predetermined position the control planes are actuated to return the bomb to said position. One form of means by which the gyroscope may 45 control the actuation of the bellows is shown in Figs. 4 and 5, and may be constructed substantially as follows.

A tank 55' of compressed air is positioned 50 within portion 24 of stem or casing 3. From said tank leads a pipe 56 having two branches 57, 58 which extend to the underside of a slide valve 59 within a casing 59'. Pipes 60, 61 lead from distributing chambers 62, 63 respectively in the top of stem 55, 53, to the upper side of said slide valve 59. Said valve is slidable within casing 59' and is adapted to open communication between one or the other of pipes 60, 61, and the tank 55' depending upon the direction of movement of said valve. In the neutral position of said valve (see Fig. 5) the pipes 60, 61 are in communication with exhaust ports 64, 65, respectively which ports are open to the atmosphere. Passages 66, 67 extend through 60 said valve, and are so positioned that when

said valve moves in one direction from its neutral position, passage 66 is brought opposite pipes 60 and 57, thus placing pipe 60 in communication with tank 55', while movement of said valve in the other direction 70 from neutral position brings passage 67 opposite pipes 58 and 61, thus placing the last mentioned pipe in communication with said tank. Flexible pipes 68 connect distributing chamber 62 with the proper chambers 75 of the respective bellows while flexible pipes 69 connect the distributing chamber 63 with the other chambers of said bellows. Said pipes 68 and 69 are sufficiently long and flexible to permit the folding of the drag 80 rudder in its inoperative position, prior to launching of the bomb. The pipes 68', 69' lead to the bellows 50'. When the bomb is in its predetermined position about its vertical axis, slide valve 59 is in its neutral position, but whenever said bomb turns away from said position said valve is actuated to place the proper chambers of the respective bellows in communication with the tank 55'. For so actuating said valve I have provided 85 means controlled by the gyroscope which shall exert a minimum resistance to the action of the latter and shall at the same time be readily responsive whenever relative turning about a vertical axis between 90 the gyroscope and bomb occurs.

One form which such means may assume is shown in Fig. 4. A link 70 is connected at one end to valve 59 and at its other to the movable member 71 of a bellows 72 which 100 comprises expandable chambers on opposite sides of said movable member, similar to bellows 50. Springs may be provided on opposite sides of members 71, as shown, to centralize the latter. Communication between tank 55' and the bellows 72 is provided by a pipe 73 which extends from pipe 56. Pipes 74, 75 which are in communication with the respective chambers of said bellows extend upwardly and terminate in small 105 nozzles adjacent a plate 76 carried by the vertical ring 27 of the gyroscope. When the bomb is in its predetermined position about its vertical axis, both nozzles are covered by said plate, but when the bomb turns 110 from said position one or the other of said nozzles is moved out from under said plate since the gyroscope does not turn with the bomb thus permitting air to escape more freely from the corresponding chamber of 115 the bellows. The pressure in said chamber is now less than that of the other chamber of the bellows, and member 71 is accordingly moved to actuate the slide valve 59 to place the proper chambers of the control plane 120 actuating bellows in communication with the tank 55'. Upon the return of the bomb to its predetermined position about its vertical axis both nozzles of pipes 74, 75 are again covered by plate 76 and member 71 is there-

upon moved back to its central position thus restoring valve 59 to neutral position. By maintaining balanced pressures on opposite sides of member 71 the device is rendered 5 highly sensitive to any differences of pressures which may be set up by the turning of the bomb and uncovering of the port 74 or 75. While disconnected from the gyroscope, it is nevertheless apparent that the sensitive 10 bellows 72 enables the gyroscope to control the fluid-pressure supply. The bellows is therefore in effect part of a pressure multiplying system controlled by the gyroscope.

As a specific example of the operation of 15 the means for stabilizing the bomb in azimuth, assume that the bomb turns clockwise, looking down. The nozzle of pipe 74 is moved from under plate 76, and the left hand chamber of bellows 72 is thus placed 20 in free communication with the atmosphere. Member 71 and valve 59 are thereupon moved to the left (Fig. 4). Communication between pipe 60 and tank 55' is now opened by passage 66 and hence compressed air is admitted to distributing 25 chamber 62 and thence to the proper chambers of the plane controlling bellows to cause turning of said planes to turn the bomb counter-clockwise. When the bomb 30 is turned back to its predetermined position, valve 59 is moved to its neutral position once more, so that port 66 is no longer in communication with pipe 60 and pipes 35 60 and 61 are again in communication with their respective exhaust openings. If now, the bomb turns from its predetermined position in a counter-clockwise direction, valve 59 is moved to bring port 67 opposite pipes 58 and 61, so that the control planes 40 are turned in the proper direction to restore the bomb to said predetermined position.

If desired, centralizing springs may be 45 provided in connection with the bellows that operate the control planes. Thus springs 82, 83 are shown on opposite sides of movable operating members of the 50 respective bellows to centralize said members. Said springs serve to prevent movement of the respective control planes away from their central position by any other 55 means than the respective bellows, said springs at the same time permitting movements of the movable member of the bellows in response to the admission of compressed air thereto from tank 55'.

Preferably the pressure of the air issuing 60 through the pipes 74 and 75 is reduced below that of tank 55 so that the pressure on plate 76 may be reduced, and for this purpose, pipe 73 may be constricted as shown at 84.

A valve 85 serves to cut off communication 65 between tank 55' and the parts of the stabilizing system until the gyroscope is spun up and unlocked. For actuating said

valve to open said communication, plunger 39 may be extended upwardly and connected to an arm 86 projecting from said valve. When piston 13 moves plunger 39 upwardly to unlock the gyroscope, valve 85 is also turned to admit compressed air from tank 55 through pipe 85' to pipes 56 and 73, and the stabilizing system is thereby placed in condition for operation.

In accordance with the provisions of the 70 patent statutes, I have herein described the principle of operation of my invention, together with the apparatus which I now consider to represent the best embodiment thereof, but I desire to have it understood 80 that the apparatus shown in only illustrative and that the invention can be carried out by other means. Also, while it is designed to use the various features and elements in the combination and relations described some of these may be altered and others omitted without interfering with the more general results outlined, and the invention extends to such use.

Having described my invention what I 85 claim and desire to secure by Letters Patent is:

1. In combination, a member adapted to be connected to a bomb, a drag rudder connected to said member, and means carried 95 by said member for retarding the opening of said drag rudder.
2. In combination, a hollow stem adapted to be connected to a bomb, a drag rudder foldably connected to said stem, and means 100 within said stem for cushioning the unfolding of said rudder.
3. In combination, a hollow stem, means for connecting said stem to a bomb, a drag rudder foldably connected to said stem, and 105 means within said stem for retarding the opening of said rudder.
4. In combination, a hollow stem adapted to be connected to a bomb, a drag rudder foldably connected to said stem, a piston 110 movable within said stem, and connecting means between said rudder and piston for causing the latter to compress air within said stem in response to the opening of said rudder.

5. In combination, a hollow stem adapted to be secured to a bomb, a drag rudder foldably connected to said stem, a piston movable within said stem, a member connected 115 to said piston for movement therewith, a plurality of cords each connected at one end to said rudder and at the other to said stem, and connections between said member and intermediate portions of said cords.

6. In combination, a gravity bomb, a 125 drag rudder, means for connecting said rudder to the bomb proper, and means including movable control planes carried by said rudder for stabilizing said bomb in azimuth.

7. In combination, a gravity bomb, a drag rudder, means for connecting said rudder to the bomb proper, and means including a gyroscope carried by said connecting means for stabilizing said bomb in azimuth. 5
8. In combination, a gravity bomb, and means positioned outside of the bomb proper for stabilizing the latter in azimuth. 10
9. In combination, a gravity bomb and means positioned outside the bomb proper comprising a gyroscope, and pneumatic means controlled by said gyroscope for stabilizing said bomb in azimuth. 15
10. Means for stabilizing a gravity bomb in azimuth comprising a control plane, an expansible member for moving said plane, a source of pressure, and means responsive to the turning of the bomb about its vertical axis for controlling the admission of pressure to said member. 20
11. Means for stabilizing a gravity bomb in azimuth, comprising a control plane, an expansible member for moving said plane, a gyroscope, and fluid pressure means controlled by said gyroscope for expanding said member. 25
12. In combination with a gravity bomb, a control surface for turning said bomb about its vertical axis, means responsive to fluid pressure for moving said surface, a valve for controlling the admission of fluid to said means, balanced pressure means connected thereto a gyroscope and means responsive to relative movement of said gyroscope and bomb about a vertical axis for disturbing said balance and actuating said valve. 30
13. In combination with a gravity bomb, a control surface for turning said bomb about its vertical axis, means responsive to fluid pressure for moving said surface, a valve for controlling the admission of fluid to said means, a movable member connected to said valve, a gyroscope, a pair of nozzles adjacent said gyroscope, fluid pressure means connected to said nozzles, means connected to said gyroscope for covering said nozzles when the bomb is in a predetermined azimuth position and for uncovering one or the other of said nozzles when said bomb moves in one direction or the other from said position, and means responsive to the uncovering of either of said nozzles for moving said member to actuate said valve. 35
14. In combination, a drag rudder, means for connecting said rudder to a bomb, means including a gyroscope carried by said connecting means for stabilizing said bomb in azimuth and means actuated by the opening of said drag rudder for spinning up said gyroscope. 40
15. In combination, a drag rudder, means for attaching said rudder to a bomb, a gyroscope carried by said means, and means actu- 45
- ated by the opening of said drag rudder for spinning up and unlocking said gyroscope. 50
16. In combination, a drag rudder, means for attaching said rudder to a bomb, means including a gyroscope carried outside the bomb proper for stabilizing the latter in azimuth, and means for simultaneously retarding the opening of said drag rudder and spinning up said gyroscope. 55
17. In combination, a drag rudder, means for attaching said rudder to a bomb, means including a gyroscope for stabilizing said bomb in azimuth, means responsive to the opening of said rudder for compressing a fluid, and means for causing the fluid so compressed to spin up said gyroscope. 60
18. In combination, a drag rudder, a hollow casing to which said rudder is foldably connected, means for connecting said casing to a bomb, a piston movable within said casing, a gyroscope carried within another portion of said casing, mechanism for spinning up said gyroscope, means for causing movement of said piston to compress air within said casing in response to the opening of said drag rudder, and means for directing the compressed air upon said mechanism to spin up said gyroscope. 65
19. In combination, a drag rudder, a hollow casing to which said rudder is connected, means for connecting said casing to a bomb, a piston movable within said casing, a gyroscope within another portion of said casing, means controlled by said gyroscope for stabilizing said bomb in azimuth, means for moving said piston in response to the opening of said rudder, means for locking said gyroscope, means for rendering said stabilizing means inoperative, and means actuated by said piston for unlocking said gyroscope and for rendering operative said stabilizing means. 70
20. In combination, a drag rudder, a bomb to which said rudder is connected, pneumatic means for stabilizing said bomb in azimuth, means for rendering said first named means inoperative, and means controlled by the opening of said rudder for rendering said first named means operative. 75
21. In combination, a drag rudder, a bomb to which said rudder is connected, a gyroscope, a source of fluid pressure, means connected to said source and controlled by said gyroscope for stabilizing said bomb in azimuth, means for cutting off communication between said source and said first named means, and means controlled by the opening of said drag rudder for establishing communication between said source and said first named means. 80
22. In combination, a drag rudder, a hollow casing to which said rudder is foldably connected, means for connecting said casing to a bomb, a piston movable within said casing, means for causing movement of said 85

- 20 piston in response to the opening of said drag rudder, a source of fluid pressure within said casing, means connected to said source for stabilizing said bomb in azimuth, a valve for cutting off communication between said source and said stabilizing means, and means comprising a movable member in the path of said piston for moving said valve to establish communication between 10 said source and said stabilizing means in response to the opening of said drag rudder.
23. In combination, a drag rudder, adapted to be connected to a gravity bomb, means for stabilizing said bomb about its 15 vertical axis, a piston movable by the opening of said drag rudder, and means controlled by said piston for placing said stabilizing means in condition for operation.
24. Means for stabilizing a gravity bomb 20 in azimuth, comprising a control plane, an expansible member for moving said plane, fluid pressure means for expanding said member, a second expansible member for controlling said fluid pressure means, and a 25 gyroscope for controlling said second member.
25. Means for stabilizing a gravity bomb in azimuth comprising a control plane, a gyroscope, and means controlled by, but disconnected from, said gyroscope for moving 30 said plane.
26. Means for stabilizing a gravity bomb in azimuth comprising a control plane, a gyroscope, an expansible member for moving said plane, fluid pressure means for expanding said member, and means disconnected from said gyroscope whereby said gyroscope controls said fluid pressure means.
27. Means for stabilizing a gravity bomb in azimuth comprising a control plane, a gyroscope, and a power-multiplying means between said gyroscope and said plane adapted to be controlled by, but disconnected from, said gyroscope.
28. Means for stabilizing a gravity bomb in azimuth comprising a control plane, a gyroscope, an expansible member for moving said plane, a fluid-pressure means for expanding said member, an expansible mem- 50 ber for controlling said fluid pressure means, and means disconnected from said gyroscope whereby said gyroscope controls said last-named member.
29. Means for stabilizing a gravity bomb in azimuth comprising a control plane, a gyroscope, a movable member for moving said plane, fluid-pressure means for moving said member, a member for controlling said fluid-pressure means, and means disconnected from said gyroscope whereby said 55 gyroscope controls said last named member.
30. Means for stabilizing a gravity bomb in azimuth comprising a control plane, means for moving said plane, a source of fluid pressure for actuating said means, means controlling said source and comprising a movable member, means for normally maintaining balanced pressures on opposite sides of said member to hold said member against movement, and means responsive to 60 turning of the bomb for upsetting the balance and moving said member.
31. Means for stabilizing a gravity bomb in azimuth comprising a control plane, means for moving said plane, a source of fluid pressure for actuating said means, means controlling said source and comprising a movable member, means for normally maintaining balanced pressures on opposite sides of said member to hold said member against movement, and means responsive to 65 turning of the bomb for upsetting the balance and moving said member.
32. Means for stabilizing a gravity bomb in azimuth comprising a control plane, means for moving said plane, a source of fluid pressure for actuating said means, means controlling said source and comprising a movable member, means for normally maintaining balanced pressures on opposite sides of said member to hold said member against movement, a gyroscope, and means whereby said gyroscope controls the pressures on opposite sides of said member.
- In testimony whereof I have affixed my signature.
- ELMER A. SPERRY.
